UNITED STATES PATENT OFFICE

152,588

DESIGN FOR A DISPENSING MACHINE

Alan D. Brundage, Detroit, Mich., assignor to
F. L. Jacobs Co., Detroit, Mich., a corporation
of Michigan

Application September 11, 1946, Serial No. 133,245

Term of patent 14 years

(Cl. D52—3)

To all whom it may concern:

Be it known that I, Alan D. Brundage, a citizen of the United States, residing in Detroit, in the county of Wayne, State of Michigan, have invented a new, original, and ornamental Design for Dispensing Machines, of which the following is a specification, reference being had to the accompanying drawing, forming a part thereof, wherein:

Figure 1 is a front elevation of a dispensing machine, showing my new design;

Fig. 2 is a side elevation of a dispensing machine, showing my new design; and

Fig. 3 is a view in perspective of a dispensing machine showing my new design.

The essential features of my design reside in that portion of the design illustrated in solid lines.

I claim:

The ornamental design for a dispensing machine, as shown and described.

ALAN D. BRUNDAGE.
